UNITED STATES PATENT OFFICE

ANDERS ERIK ALLANSON STRÖMBERG, OF STOCKHOLM, SWEDEN, ASSIGNOR TO NYA AKTIEBOLAGET GALCO, OF STOCKHOLM, SWEDEN, A CORPORATION

SELF-CLOSING OIL CUP

Application filed January 26, 1928, Serial No. 249,633, and in Germany February 1, 1927.

The present invention relates to the kind of self-closing oil cups in which the spring-operated lid is provided with a depending flange encircling the upper rim of the cup.

5 One of the advantages characterizing oil cups with lids of this kind is that they efficiently prevent dust from entering the cup. The essential object of the invention is the provision in such cups in a suitable and 10 cheap manner from a manufacturing point of view of means for fastening the upper end of the spring to the lid without the necessity of deforming the lid in any way whatever or providing it with holes, slots or 15 the like.

In the accompanying drawing four embodiments of the invention are shown by way of example on an enlarged scale, Figures 1-5 showing one of the embodiments of 20 the invention, Figures 6-9 the second embodiment, Figures 10-14 the third embodiment and Figures 15 and 16 the fourth embodiment.

Figure 1 shows the oil cup in vertical section with the lid in the open position, Figure 2 shows the inside and the bottom of the cup and Figure 3 the upper cup-shaped plate for the fastening of the spring. Figure 4 is a side elevation of the plate viewed 30 at right angles to Figure 3. Figure 5 shows the lid from the side before receiving the plate for fastening the spring. The Figures 6, 7 and 8 are illustrations corresponding to the Figures 1, 3 and 4 of the second embodiment. Figure 9 shows the lid in section.

Figure 10 is a view corresponding to Figure 1. Figures 11 and 12 show the plate from the side and from above respectively. Figures 13 and 14 show the lid in vertical 40 section and from above respectively. Figure 15 is a vertical sectional view of the lid plate and Figure 16 is a horizontal view of the plate, shown in Figure 15.

1 is the oil cup, 2 the lid and 3 the spring, 45 which tends to bring the lid into the closed position or to keep it there.

The plate serving for the fastening of the upper end of the spring bears the reference number 4.

50 The dimensions and the shape of the plate

are such that when pressed down into the depression in the lid in a direction towards the inside of the upper or flat part of the lid the sides of the plate are brought into frictional engagement with and securely held by the flange 5 of the lid, said flange in the closed position of the lid encircling the upper part of the cup 1. For this reason the plate should have a somewhat larger diameter than the inner diameter of the flange 5. If, however, the plate is cup-shaped, that is slightly curved in a downward direction as shown in the drawing at 6, the diameter of the plate may originally be equal to or even slightly less than the diameter of the inside of the flange 5, the pressure of the pressing tool against the convex side of the flexure 6 when the plate is pressed down into the lid having the effect of somewhat increasing the diameter of the plate. In addition the curved part 6 of the plate 4 has the object of guiding the lid towards the centre of the cup when the lid is closed under the action of the spring. This is of particular importance if the free end of the flange 5 of the lid is not turned out as shown in the figure, but is made fully cylindrical, as it may happen that the flange of the lid does not come down over the cup but is caught on the rim of the cup, unless the plate is cup-shaped. When the plate 4 is made a lug 7 or the like is stamped out of it, the upper end of the spring being brought into engagement with this lug when the lid and the cup are put together.

When the cup 1 is pressed two holes 9 are stamped out in its bottom (Figure 2), so that a preferably up-turned bridge 8 is formed. The lower end of the spring is brought into engagement with this bridge. In this way the insertion of a separate pin or the like in the bottom of the cup is avoided.

In this way of carrying out the invention the lid is provided with a projection 10 which serves as a handle and the underside of which is engaged when the lid is opened. The shape of the plate 4 is such, that the space 11 between the flange 5 of the lid and the curved part of the plate is comparatively small in order that the lid, when the cup is opened,

may be displaced in a lateral direction to a very small extent only.

The construction according to the Figures 6-9 differs from that already described mainly in that the projection 10 on the lid serving as a handle has been left out and that the space 11 is somewhat larger.

The free end of the flange 5 on the lid is preferably slightly widened to facilitate the lifting of the lid and in order that the latter may easily be turned in any desired direction.

In the construction shown in the Figures 10-14 the plate 4 is quite flat but is provided with a lug 12 stamped out of the plate and bent down, into which the upper end of the spring engages. The longitudinal direction of this lug is approximately perpendicular to a diameter passing through the centre of the handle of the lid, the lug being nearer the end of the diameter opposite the handle than the point on the lid from which the latter projects (see Figures 10 and 12).

In the construction shown in the Figures 15 and 16 the lug 7 is stamped out of a depression 13 in the plate 4, said depression sloping from the end nearest the handle to the opposite end.

What I claim is:—

30 1. Self-closing oil cup in which the spring-operated lid is provided with a depending flange encircling the upper rim of the cup, characterized in that the means for fastening the upper end of the spring comprises a plate (4) pressed down into the lid, said plate being retained in its position by frictional engagement with the flange (5) of the lid.

35 2. A self-closing oil cup of the type including a lid having a depending flange for encircling the upper rim of the cup, a closing spring, and means carried by the lid for connecting the spring thereto, characterized by the fact that the depending flange of said lid retains the said means within the lid by frictional engagement therewith.

40 3. A self-closing oil cup as set forth in claim 2, wherein the said means has a lug depending therefrom for receiving the end of the spring, said lug being off-center with respect to the rim of the cup and cooperating with the adjacent portion of the flange to provide a loose hinge connection between said lid and cup.

45 In testimony whereof I affix my signature.

50 ANDERS ERIK ALLANSON STRÖMBERG.
